UNITED STATES PATENT OFFICE.

CHARLES VALLANDIGHAM MARTIN, OF MOXAHALA, OHIO.

ROTARY STEAM-ENGINE.

SPECIFICATION forming part of Letters Patent No. 417,196, dated December 10, 1889.

Application filed June 20, 1889. Serial No. 314,920. (No model.)

To all whom it may concern:

Be it known that I, CHARLES VALLANDIGHAM MARTIN, a citizen of the United States, and a resident of Moxahala, in the county of 5 Perry and State of Ohio, have invented certain new and useful Improvements in Rotary Steam-Engines; and I do hereby declare that the following is a full, clear, and exact description of the invention, which will enable 10 others skilled in the art to which it appertains to make and use the same.

The invention relates to improvements in rotary steam-engines; and it consists in the construction and novel combination of parts 15 hereinafter described, illustrated in the drawings, and pointed out in the appended claims.

In the accompanying drawings, in which similar letters of reference refer to corresponding parts, Figure 1 is a central vertical 20 longitudinal section of a steam-engine embodying my invention. Fig. 2 is a central horizontal section of the same. Fig. 3 is a transverse section through the cylinder. Fig. 4 is a detail sectional view of the reversing- 25 valve. Fig. 5 is a detail sectional view of the abutment chambers and plates. Fig. 6 is a detail perspective view of the central packing-ring; and Fig. 7 represents detail sectional 30 views of the cylinder, piston, arms *d*, packing-ring, and block *e*.

Referring to the drawings by letter, *A* designates the bed of the machine, of suitable shape, but preferably rectangular generally, and having bearings at suitable points for 35 the main or driving shaft *B*, as shown.

C is a circular cylinder, of suitable cross-section, secured to the bed by proper means and having the central space *c* within it for rotation of the piston-block *D*, which block 40 is secured to the adjacent end of the shaft *B* and has the arms *d* extending through the circumferential opening from the central space *c* into the piston-way *c'* of the cylinder. The cylinder is preferably circular in cross-section. The piston-block is surrounded by 45 a packing-ring *d'*, triangular in cross-section, resting against a shoulder on the block and with its edge bearing on the packing-ring of the piston. Between said arms is secured 50 the piston *E*, of suitable shape to fit within the way *c'*, there being an opening through the piston and registering openings in the

arms *d*, so that a pin or bolt can pass through the said openings and attach the piston to the arms. The opening in the piston is larger 55 than said bolt to permit the piston to travel truly in the piston-way *c'*. A packing-ring *e* rests against and surrounds the piston, the said ring being suitably spliced between the arms *d*. The splice is covered by a block *e'*, 60 that stands between the side plates that compose the piston.

The shaft *B* passes through a stuffing-box *F*, standing centrally from the adjoining side of the cylinder and having an inwardly-tapered interior space, into which the sets of semicircularly-sectioned packing-rings *f* are inserted and respectively break joints with each other. The said rings can be tightened in their seat by disk *f'* and screws passing 70 through said disk and engaging in threaded openings in the edge of the stuffing-box.

The piston-block *D* has its end that connects to the shaft conical or beveled, so that a circular steam-chamber *g* is formed in the 75 adjacent central part *c* of the cylinder, into which chamber the steam-port *G* opens, as shown. The piston-block is provided with the axial recess *H*, of suitable diameter, aligned with the main shaft, from which extend the 80 similar ports *h h*, arranged at a suitable angle to each other and giving communication between the recess *H* and the piston-way *c'*. The piston-block is also provided at its tapered end with the steam-duets *h'* leading 85 from the end of the recess *H* into the steam-chamber *g*, as shown, and taking steam into said recess.

An exhaust pipe or port *I* stands laterally from a hollow box *i*, flanged outwardly at its 90 edge and packed and bolted at said flange upon the outer side of the cylinder over the mouth of the recess *H*, so that the said recess and exhaust-port can communicate.

J is a valve seated in the recess *H* and provided with a diagonal or inclined partition *j*, which extends from its inner end toward its front and has the openings *j' j''* on each side of it. The outer end of said valve is provided with a circumferential flange *j''*, fitting 100 in a corresponding recess in the recess *H* and resting against the outer wall of the central space *c*.

K is a rod passing axially into the recess *H*

and valve J and squared where it passes through the partition j to cause the valve to turn with it and at the same time not be bound longitudinally thereon. The partition 5 is provided with a shoulder j^4 on its faces, and the rod K has a nut that rests against said inner shoulder and prevents the passage of steam through the opening in the partition. The said rod has on its outer end a 10 hand-wheel or lever, as shown, and on its inner end a lateral projection k at right angles to its stem and resting in a groove k' , that is at the end of the recess H, which communicates with the steam-ducts h' .

15 The rod K passes through a stuffing-box standing outward from the base of the box i and preventing the escape of steam.

Standing from the cylinder at opposite points, separable or integral therewith and 20 parallel to the main shaft, are the abutment-chambers L, that open into the piston-way, and within said chambers are the abutment-plates M M, preferably rectangular, which have their inner edges that rest against the piston-block thicker than their outer edges, so that the said plates appear wedge-shaped when viewed edgewise. This reduces wear 25 on the piston-block. The said abutment-plates are secured at their edges to the abutment-rods N, which pass through stuffing-boxes n at the ends of the corresponding abutment-chambers L, and thence extend through suitable guides secured to the bed or frame of the engine. The abutment- 30 plates M, when in the cylinder, rest in suitable recesses or seats m in and transverse to the cylinder. To the rods N are secured the curved director-shoes O, from which stand inward fingers o, that preferably have anti-friction rollers mounted on them. The said shoes fit upon the surface of a cam-wheel P, of suitable construction, secured to the main 35 shaft, and the anti-friction rollers enter the cam-groove p of the said wheel, which groove 40 has the inclined portion p' , so shaped and situated that as soon as the piston passes an abutment-chamber the corresponding abutment-plate is forced into the cylinder behind it, and as soon as the steam is exhausted from 45

the cylinder on the side of the plate opposite 50 the piston the piston is withdrawn from the cylinder. The ports h extend from the recess H at such an angle to each other that both will open on the same side of the opposite abutment-plates at proper times, so that 55 one will deliver steam behind the piston and the other will exhaust before the piston.

The steam enters through the ports G, chamber g , and steam-ducts h' into the groove k' , whence it passes through the opening j' on 60 the inner side of the partition j of the valve J into the adjacent port h , and thence into the piston-way c' behind the piston. The exhaust-steam escapes through the opposite port h into the opening j^2 on the outer side of the 65 partition j , thence into the recess H, and thence from the exhaust-port I.

It is obvious that by turning the valve J one-half way round in the recess H by means of its rod and hand-wheel the relation of the 70 openings $j' j^2$ to the ports h will be reversed, and consequently the piston will rotate in the opposite direction or the engine will be reversed. A quarter-turn will stop the engine, as the ports will then not register. 75

Having described my invention, I claim—

1. The combination, with the piston and piston-block having the recess H, ports h , ducts h' , and groove k' , of the valve J, having the partition j and openings $j' j^2$, and the valve-rod K, having a hand-wheel on its outer end and the projection k on its inner end, substantially as specified. 80

2. The combination, with the cylinder, main shaft, cam-wheel, piston-block provided with 85 recess H, ports h , ducts h' , and groove k' , of the valve J, having the partition j and openings $j' j^2$, the abutment-chambers, abutment-plates, abutment-rods, and director-shoes attached to said rods, substantially as specified. 90

In testimony that I claim the foregoing as my own I have hereunto affixed my signature in presence of two witnesses.

CHARLES VALLANDIGHAM MARTIN.
